Primary Examiner — Wan Laymon*(74) Attorney, Agent, or Firm* — Novak Druce Connolly Bove + Quigg LLP(57) **CLAIM**

The ornamental design for an eye and face wash system, as shown and described.

DESCRIPTION

FIG. 1 is a perspective view of an eye and face wash system, shown having a thermoplastic bowl and without a pedestal attachment;

FIG. 2 is top elevation view thereof;

FIG. 3 is a bottom elevation view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a perspective view of an eye and face wash system, shown having a metal or composite bowl and without a pedestal attachment;

FIG. 9 is a top elevation view thereof; and,

FIG. 10 is a bottom elevation view thereof;

FIG. 11 is a front elevation view thereof;

FIG. 12 is a rear elevation view thereof;

FIG. 13 is a right side elevation view thereof; and,

FIG. 14 is a left side elevation view thereof.

The following are illustrative of environmental structure for and form no part of the claimed design.

The hinge connections coupled to the eye wash and face wash spray covers.

The strainer shapes and configuration.

All broken lines shown in the drawings.
